UNITED STATES PATENT OFFICE

BLADEN M. SHORT, OF DETROIT, MICHIGAN, ASSIGNOR TO GENERAL SPRING BUMPER CORPORATION, OF DETROIT, MICHIGAN, A CORPORATION OF MICHIGAN

DESIGN FOR AN IMPACT BAR FOR AUTOMOBILE BUMPERS

Application filed November 28, 1932. Serial No. 46,189. Term of patent 7 years.

To all whom it may concern:

Be it known that I, BLADEN M. SHORT, a citizen of the United States, and a resident of the city of Detroit, in the county of Wayne and State of Michigan, have invented a new, original, and ornamental Design for an Impact Bar for Automobile Bumpers or Similar Article, of which the following is the specification, reference being had to the ac-

companying drawing, forming a part thereof.

In the drawing:

Figure 1 is a front view of the impact bar.
Figure 2 is a plan view of the impact bar.

I claim:

The ornamental design for an impact bar for automobile bumpers as shown.

BLADEN M. SHORT.
